(57) **CLAIM**

The ornamental design for a motorcycle or motorcycle replica, as shown and described.

DESCRIPTION

FIG. 1 is a front and left side perspective view of a motorcycle or motorcycle replica showing our new design; FIG. 2 is a rear and left side perspective view thereof; FIG. 3 is a front and right side perspective view thereof; FIG. 4 is a rear and right side perspective view thereof; FIG. 5 is a left side elevation view thereof; FIG. 6 is a right side elevation view thereof; FIG. 7 is a front elevation view thereof; FIG. 8 is a rear elevation view thereof; FIG. 9 is a top plan view thereof; and, FIG. 10 is a bottom plan view thereof.

The broken lines shown in the drawings illustrate portions of the motorcycle that form no part of claimed design.

1 Claim, 10 Drawing Sheets
